FEATHER TREATMENT

Bohumil Bouda, Davenport, Iowa

Application May 23, 1938, Serial No. 209,497

7 Claims. (Cl. 19—4)

The present invention relates to the production of down and more particularly to processes and apparatus for the stripping of feathers for the production of down.

In this country, one may obtain so called down pillows and cushions by the payment of substantially higher prices than for the same article admittedly stuffed with feathers. This so called down is obtained by removing first the large feathers from the bird and then removing the small feathers. The latter are employed generally in the condition they are obtained from the bird. It has been attempted to improve the condition of feathers by comminuting them, the feathers being cut across the shafts so as to divide them up into several sections. This has proven to be a distinct failure. The feathers so produced are just as heavy as prior to comminuting. Pillows produced from the comminuted product are just as hard as though produced from normal feathers. In addition to these lacks of advantage, the cut ends of the shafts protrude through the casing during use and are more objectionable than normal feathers since they scratch instead of rub.

In Europe the situation is quite different. A manual operation is performed on the feathers which is termed "stripping," in which each feather is held in one hand by the outer end and the barbs near this end are grasped with the other hand and pulled away from the outer end. By this procedure, the barbs of the feather are removed from the shaft which is discarded. In this operation, a small section of barbs remains at the outer end which it is impossible to strip. Due to the general lack of patience of the people in this country and their desire to have all tasks done by others, no substantial quantity of stripped feathers is here produced.

It is accordingly an object of the present invention to provide processes and apparatus for the stripping of feathers; i. e., for the removal of barbs from shafts.

Further objects will be apparent from a consideration of the following description taken in conjunction with the accompanying drawings.

Feathers are composed of two main parts, the shaft and the barbs. The shaft is constituted of the quill or part which attaches the feather to the skin of a bird and the rachis or part to which the barbs are attached. For convenience in this description, the end of the feather at which the quill is located is termed the "quill end" and the other end is termed the "outer end."

In accordance with the present invention, a feather is gripped initially at its quill end, the point at which the feather is gripped being moved along the feather progressively toward the outer end and the barbs being moved relatively to the shaft, toward the quill end, until pulled from the shaft, the barbs at the quill end being moved first and being gripped progressively along the length of the feather toward the outer end.

10. Suitable devices for carrying out the process of the present invention and machines forming the subject matter of this invention are shown in the accompanying drawings forming a part of this application. In the drawings,

15. Fig. 1 is an elevation of a machine in accordance with the present invention, with parts broken away better to show the structure;

Fig. 2 is a vertical section substantially on the line 2—2 in Fig. 1, showing the feather stripper employed in the machine for the stripping of coarse feathers;

20. Fig. 3 is a vertical section substantially on the line 3—3 in Fig. 1, showing the feather stripper employed in the machine for the stripping of fine feathers;

25. Fig. 4 is an elevation of the stripper shown in Fig. 3 with parts broken away and partially in section on the line 4—4 of Fig. 3 to show the driving mechanism;

30. Fig. 5 is an elevation of a portion of the stripping roll;

Fig. 6 is a section substantially on the line 6—6 in Fig. 5;

Fig. 7 is a section substantially on the line 35. 7—7 in Fig. 2;

Fig. 8 is a longitudinal section through a modified form of feather stripper; and

Fig. 9 is a section through another modified form of feather stripper.

40. Referring to Fig. 1, the machine of the present invention involves, in general, a feather separator 9, a pair of stripping mechanisms 10, and a down collector 11. The feather separator 9

45. comprises a feather hopper 12 for receiving the raw feathers and has at its lower end a wheel 14 provided with pins 15 for feeding the feathers gradually into the main compartment of the separator. An air inlet 16 is positioned in a side 50. wall of the separator compartment below the wheel 14 and is provided with a valve 17, to adjust the force of the air stream, and with a plurality of plates 18 or the like by which the flow of air into the compartment is controlled to eliminate eddy currents. The separating compart-

ment is provided with an outlet 19 in the opposite end thereof from the air inlet 16 and with a divider 20 in the bottom of the compartment between the inlet 16 and the outlet 19. The outlet 19 communicates by a pipe 21 with a down receiving bag 22 positioned in a suction box 23 which is in communication with the inlet end of suction fan 24. The bag 22 is of fabric or the like which allows the ready passage of air therethrough but prevents the escape of the down. The outlet end of the suction fan 24 communicates with a dust-receiving box 25 which removes the residual dust from the air circulating through the system.

An outlet 26 is positioned in the lower portion of the feather separator between the air inlet 16 and the divider 20 to receive the coarse feathers, and a second outlet 27 is positioned between the divider 20 and the outlet 19 to receive the finer feathers which drop through the stream of air and are not carried into the receiver 22 with the down. However, in this connection it should be noted that some of the extremely fine feathers may be carried by the air with the down into the receiver 22.

Coarse feather stripper 28 comprises a casing 29 which encloses a drum 30 into which the outlet 26 discharges coarse feathers. This drum is provided with openings in its surface which are large at their inner end, taper to a minimum diameter near the outer surface of the drum and are again enlarged toward the outer surface. In order to reduce the area of the inner surface as many holes should be provided as conveniently possible, as by arranging the holes in offset rows. Also, the inner ends of the openings may be hexagonal, whereby the surface between openings may be reduced to a sharp edge. This drum is mounted to rotate counterclockwise, as shown in Fig. 2. An agitator 32 is mounted coaxially with the drum to oscillate therein and has a plurality of arms 33 extending into proximity with the inner surface of the drum. These arms 33 act upon the feathers to assist in working the feathers through the drum.

I have found that a drum of the character above described allows the passage of feathers, quill end first, through the openings so that all the feathers are arranged in one direction. A feed wheel 35 is positioned below the feather receiving drum and has a plurality of radially extending arms 36 secured thereto. This feed wheel 35 and its arms 36 are of rubber and the arms are of a length to press lightly against or move in close proximity to the surface of a grooved plate 37 positioned at one side thereof. The feathers which extend from the drum are caught between the feed wheel 35 and the grooved plate 37 and are drawn thereby down to the lower end of the plate, the grooves 38 keeping the feathers in line. A relatively slow moving feed roll 39 having a longitudinally fluted, metallic surface is mounted for rotation in the machine frame and is positioned in proximity to the lower end of the plate 37. A second feed roll 40 having a rubber surface is mounted to rotate in the upper ends of a pair of arms 41 which are pivoted on a pair of stub shafts 42 carried by the frame. The arms 41 are provided at the lower end of each with an opening 43 in which a hook on a rod 44 is positioned, said rod passing through the machine frame and being provided with conventional spring tensioning means to tension the roll 40 against feed roll 39. By the above described means, feathers are ar-

ranged, quill ends first, and fed in this position at a regular speed.

Immediately below and adjacent to the feed rolls 39 and 40 is located a feather stripping roll 45 formed of a substantially rigid material, such as steel, and provided with a series of grooves 46 of size suitable to receive the shafts of feathers, the size depending upon the size of feathers to be fed to the particular roll. As shown in Fig. 5, 10 the roll is provided with square bottom grooves. This particular shape is not essential to obtaining the desirable results of the present invention. Any other shaped grooves may be used which allows adequate room for the reception of the 15 shafts of the feathers to be fed to the roll. This roll 45 is further provided with knurling 47 on the lands between the grooves. While the well known fine knurling is very suitable for the purposes of the present invention, any other roughening of the surface may, within the scope of 20 this invention, be employed. A pressure member 48 is provided, in the form of a belt to press against a substantial portion of the periphery of the stripping roll 45. This belt 48 is arranged 25 to be pressed against the roll 45 by a pair of pinch rollers 49, 50, each of which is rotatably supported in the upper end of a pair of arms 53, 54 which are pivoted upon stub shafts 55, midway of the length of each. The lower ends of the 30 arms 53, 54 are provided with openings in each of which is secured a hook 57 which passes through the machine frame and is provided with spring tensioning means 58 to press the rolls 49, 50 against the stripping roll 45. An additional pair of rolls 51, 52 is mounted on a pair of rocker arms 59, each of which is centrally pivoted to one of a pair of levers 60. The levers 60 are pivoted at 61 and are arranged with an opening at the lower end in which the spring 62 is located, which spring is backed by an adjustment screw 63 by which the tension on the rolls 51, 52 may be adjusted. In order to tension the 40 belt 48, a further roll 64 is provided at the opposite end of the belt from the stripping roller. 45 The roll 64 is mounted on a pair of arms 65 pivoted at 66 and provided at the opposite end from the roll 64 with an opening 67 and spring tensioning means 68 of conventional form. By means of the stripping roll 45 and the pressure member in the form of belt 48, operating in conjunction with feed rollers 39, 40, the barbs are stripped from the shafts of feathers and both barbs and shafts are discharged at the left side of the roll 45.

55 In order to separate the down from the shafts, an opening 69 is provided adjacent the outlet between the stripping roll 45 and the pressure member 48, which opening is in an end of the suction pipe 70. Referring to Fig. 1, the suction pipe 60 70 communicates with a collecting bag 71 in the suction box 23. In this bag 71, all down stripped from the shafts is separated from the air and retained until desired. Due to the stiffness of the quills, the shafts are fed upwardly away from the opening 69 and are deflected also, in part, by the arcuate member 72 to a belt 73 between which and the arcuate member the shafts are caught. This belt 73 is carried and driven by a pair of rolls 74, 75. This belt draws the shafts 65 into the inlet of suction pipe 76 which communicates with a collector 77 in the suction box, similar to the collectors 22 and 71.

70 While the feather stripper 28 above described in detail is particularly adapted to the stripping of coarse feathers, it should be remembered in

this connection that this feather stripper may be used for either fine or coarse feathers, even though it is best suited to the coarse feathers. For small installations where a single feather stripper is to be employed and no separation of the feathers into coarse and fine feathers and down is to be effected, a single stripper of the character above described may be employed to strip all the feathers or, if preferred, another stripper, as described below, may be employed.

The fine feathers from the separating compartment are fed through the outlet 27 therefrom to a stripper 78 particularly adapted for fine feathers. This stripper involves a drum located in a compartment similar to the compartment 29 of the stripper 28. The drum is somewhat similar to the drum 30 of the previously described stripper. However, the openings 79 in this drum 80, instead of being radial as the openings in the previously described drum, are positioned at an angle to the radius. The outer ends of the openings trail the inner ends of the openings as the drum rotates in clockwise direction, as seen in Fig. 3. This drum is provided with an oscillating agitator 32, the same as previously described. A plurality of plates 81 are located adjacent the lower surface of the drum perpendicular to the axis thereof to hold the feathers which protrude from the drum in alignment. Also positioned below the drum 80 is a suction chamber 82 provided with a pipe 83 communicating with the suction box 23. The end of the suction chamber 82 adjacent the plates 81 is open. An open-work fabric belt 84 is positioned about the suction box 82 and is provided with a roll 85 which holds the fabric belt taut and in position adjacent the plates 81. An idle rubber covered feed roll 86 is positioned adjacent the roll 85 and is supported for free rotation in arms 87 reciprocable in supports 88. The supported end of the arms 87 are hollow and house springs 89. Adjustment screws 90 are screw-threadedly mounted in the supports 88 to press against the springs 89 and tension the feed roll 86 away from the support 88. A feed roll 91 is mounted in fixed position for rotation in contact with the feed roll 86. The surface of the feed roll 91 is metal and the roll is longitudinally fluted in order to hold the feathers and feed them at a fixed rate.

A stripping roll 92, similar to the stripping roll 45 heretofore described, is positioned below and adjacent to the feed rolls 86 and 91. A pair of pinch rolls 93 and 94 hold a pressure belt 95 against the feed roll 92 and around a substantial portion thereof. The belt 95 is spring tensioned by means of an idle roll 96 mounted in one end of each of a pair of arms 97, pivoted on supports 98. An adjustment bolt 99, screw-threaded in the frame of the machine, adjustably presses against a spring 100 which presses against the lever 97 to retract the roll 96 and place tension on the belt 95. Since roll 93 is rotatably mounted at one end of each of a pair of arms 101, which are pivoted at their opposite ends at 102, in a position so that the arms extend outwardly from a position tangential to the stripping roll 92, tensioning of the belt 95 causes roll 93 to press belt 95 against the stripping roll 92. An additional pair of pinch rolls 103, 104 is positioned to bear against the belt 95 between the pinch rolls 93 and 94. These pinch rolls 103, 104 are mounted for rotation in the ends of a rocker arm 105 which is centrally pivoted to a lever 106 which, in turn, is pivoted at 107. Compression spring 108

is mounted in an opening in the lever 106 to turn the lever 106 in a direction which presses the rolls 103, 104 against the belt 95. A bolt 109 is screw-threadedly mounted in a frame member to press against spring 108 with a selectively adjustable force.

As viewed in Fig. 3, the shafts and barbs stripped therefrom are discharged together from between the stripping roll 92 and the belt 95 at the left side of the roll. The shafts are directed by a plurality of deflectors 110, 111, 112, and 113 to follow the belt 95 around the roll 94. The deflector 113 forms one side of the open end of a suction pipe 114 which communicates with suction pipe 76 which carries the shafts from stripper 28. The side 115 of the open end of suction pipe 114 opposite the deflector 113 is spaced slightly from the belt 95 to allow a stream of air to enter pipe 114 between this side 115 and the belt, thereby preventing any shafts from clinging to the belt.

The deflectors 110 and 112 constitute two sides of the open end of suction pipe 116, and have the deflector 111 positioned between them to form two openings, one between the deflectors 110 and 111 and the other between deflectors 111 and 112. The streams of air through these openings, produced by suction in pipe 116 which is connected to pipe 76, act to remove the barbs from the belt 95 and thereby separate the barbs from the shafts from which they have been stripped.

Referring now to Fig. 4 which shows the drive mechanism for the stripper 78, the power is delivered to the stripper through a pulley 117 keyed to the shaft 118 of stripper roll 92. A gear 119 is also keyed to shaft 118 and engages a gear 120, being large relatively to the gear 119. Further speed reduction is effected through a gear 122 keyed to the shaft 121, the gear 122 being in engagement with a relatively large gear 123 keyed to the shaft 124 of the fluted metallic feed roll 91. The gear ratios should be such as to drive the feed roll 91 at a substantially lower peripheral speed than the stripping roll 92.

The belt 95 and the pinch rolls 93, 94, 103, and 104 are driven by contact of the belt with the stripping roll 92. Similarly, the pinch roll 86 and the belt 84 are driven by contact of the pinch roll with the feed roll and of the belt with the pinch roll 86.

A gear 125 is keyed to feed roll shaft 124 and is in driving engagement with a gear 126 keyed to shaft 127 journaled in the frame of the machine. Shaft 127 is also provided with a gear 128 keyed thereto in driving engagement with a gear 129 mounted to rotate freely on sleeve 130 carried by the machine frame. The drum 80, into which the feathers are fed, is attached, as by rivets 131, coaxially to the gear 129 to be rotated with this gear. A shaft 132 extends through the sleeve 130 and is provided with a crank arm 133 on its outer end, the agitator 32 being secured to the inner end of shaft 132. A link 134 is connected to the crank arm 133 by a pin 135 and to the gear 126 by a pin 136 positioned eccentrically thereof, so that rotation of gear 126 oscillates the agitator.

As the details of the drive mechanism for the stripper 28 are, in general, the same as for the stripper 78, this mechanism is not illustrated, the only substantial difference being the addition of gear drives for the rotating member 35 and the roll 74 which are driven from one of the rotating shafts.

When the mechanism of the present invention

is employed, no preliminary separation of the feathers during picking of the birds is necessary. The feathers to be stripped are delivered directly to the hopper 12 from which they are fed by the wheel 14 into the air stream admitted through the opening 16 in the side of the separating compartment. The lightest materials, that is, the slight amount of natural down and a few of the extremely small feathers, are carried by the stream of air through conduit 21 into separator 22. The remaining feathers, which constitute almost the entire bulk of the feed to the hopper, are classified by the separator into coarse feathers, which drop into the opening 26, and fine feathers, which drop into the opening 27, in each instance being fed into a stripper.

The feather shafts from the strippers are drawn by suction through the conduit 76 into the separating bag 71 in which they collect. The barbs of the feathers are drawn by suction through conduit 78 into a separating bag 71. When it is desired to unload the bags 22, 71, and 77, the shutters at the lower ends of the bags which extend through openings in the floor of the suction box are opened and the materials are removed separately from each of the bags. The down in bag 71 is of higher grade than even the material collecting in the bag 22. The feather shafts from the bag 77 may be disposed of as desired.

In the stripper 28 which handles the coarse feathers, the feathers are worked through the openings 31 in drum 30, due to rotation of the drum. The oscillator 32 may be used, if desired, to increase the rate at which the feathers work through the openings, though this oscillation is used merely to speed up production. The quill ends only of the feathers work through the openings, since, due to the construction of feathers, it is virtually impossible for a feather to work its way through an opening outer end first. The quill ends are caught between the arms 36 of the rotating member 35 and the grooved plate 37 and are drawn thereby, being kept in line by the grooves 38, to the feed rolls 39 and 40, in which they are firmly gripped and fed at an even rate. As the feathers protrude from between the feed rolls, the quills lodge in grooves 40 in the stripping roll 45 and slide freely therein. As the feathers feed farther, the knurled lands 47 between the grooves, in conjunction with the belt 48, grip the barbs of the feathers and start pulling them toward the quill end. Upon further pulling of the barbs, they are eventually detached before they arrive at the outlet from the means gripping the barbs. It should be noted that the first barbs detached are those adjacent the quill and that subsequently the barbs farther up the shaft are removed. When the feed rolls free the very outer end of the feather, the section not yet stripped, i. e., the section between the feed rolls and the stripping roll, will fail to be stripped. This, however, is a very small proportion of the total barb area of the feathers and the amount lost does not exceed the loss under hand operation.

In order to increase the capacity of the machine, the member 35 may be driven at a substantially higher peripheral speed than feed roll 39. When so operated, the member 35 will carry the ends of the feathers to the left of roll 39, as seen in Fig. 2. In order to hold the feathers in line during such high speed operation, plates 34 are provided between member 35 and roll 39.

The barbs, after being stripped from the shafts

by stripping roll 45, are then separated by suction from the shafts, and both barbs and shafts are conveyed to the separating bags where they are separated from the air.

5 In the stripper 78, the finer feathers are fed into the drum 80, and from there are fed through openings 79 as in the case of the drum 30. As the protruding quills come around to the belt 84, they are guided between plates 81 in order to hold them straight. The suction through the belt 84 causes the protruding feathers to cling thereto and be drawn the rest of the way out of the drum. The belt 84 carries the feathers to the feed rolls 86 and 91, which operate in conjunction with the stripping roll 92, as above described in connection with stripper 28. The barbs are separated by suction from the shafts and both shafts and barbs are conveyed to the collecting bags and separated from air.

20 In order to illustrate the broad scope of the present invention and to show other machines suitable for the performance of the process hereof, two other feather stripping machines are disclosed in Figs. 8 and 9. In the machine shown in Fig. 8, hopper 150 is provided with a screen bottom 151 and is connected by a link 152 to a wheel 153 to effect reciprocation of the hopper. An agitator 154 is pivoted on pin 155 at the lower end of lever 156 which is pivoted on a fixed pin 157 midway of its length. A link 158 is pivoted to the upper end of lever 156 and is also connected eccentrically to rotating wheel 159 to effect oscillation of the lever 156 and agitation of the member 154.

35 Below screen 151 an endless fabric belt 160 is positioned which extends around two rolls 161, 162. A box 163 is positioned between the rolls 161 and 162 and is provided with an open upper side, the edges of which are in proximity to the belt. The belt is of a fabric of such nature that air is drawn therethrough by the suction box whereby feathers are held in position on the belt. As the feathers work through the screen 151 gradually, and the belt 160 is in constant motion in one direction, the quill ends of the feathers are dragged along by the belt until they are entirely disengaged from the screen, at which time they will drop down on the belt and be fed thereby, quill end first. An air baffle 164 is mounted on the hopper at the outlet end of the upper run of the belt 160 to prevent air currents from disarranging the feathers on the belt.

Also positioned at the outlet end of the upper run of belt 160 is a longitudinally fluted metallic feed roll 165 which, in accordance with a preferred form of this invention, is driven and effects the driving of the belt 160 by pressure thereagainst. In line with the outlet of feed roll 165 and belt 160 which cooperates therewith, the machine is provided with a stripping roll 166 of the character previously described. A soft rubber roll 167 is mounted to press against roll 166 with sufficient force that rolls 166 and 167 are in contact for a substantial portion of the periphery of the stripping roll 166. Rolls 166 and 167 are driven at a considerably higher peripheral speed than feed roll 165. A suction conduit 168 opening adjacent roll 167 is provided to remove the barbs from rubber roll 167. A deflector 169 is positioned adjacent the outlet from the stripping roll to guide the shafts to wheel 170 provided with a plurality of arms, which, upon rotation, throws the shafts clear of the machine.

70 The stripper shown in Fig. 9 involves a hopper

171, the lower end of which is provided with bars 172 lengthwise and bars 173 crosswise. The lengthwise bars are vertical whereas the crosswise bars are set at an angle to the vertical with the lower edge bent toward the outlet end of the machine. An agitator 174 is pivoted to a lever 175 which is pivoted at its upper end to the hopper and is provided with a pin 176 intermediate its length to which a link 177 is pivoted. The link 177 is pivoted at its opposite end to a wheel 178, eccentrically thereof, whereby rotation thereof will cause agitation of member 174. An endless belt 179 is disposed immediately below the bars 172 and 173 sufficiently closely that bars 173 will hold the feathers against the belt and prevent their disarrangement. The belt is mounted to travel on three rolls, one roll 180 at the inlet end of the belt 179 and two at the outlet end. A fluted feed roll 181 and cooperating pinch roll 182, as previously described, are positioned in proximity to the outlet of the belt. A substantially vertical conduit, a portion of which is defined by belt 179 and by rolls 181 and 182, communicates with hopper 171 whereby feathers not lying longitudinally will be returned to the hopper by a current of air passing through the conduit. A stripper roll 183 and cooperating endless belt 184, similar to those described in connection with feather strippers 28 and 78, are positioned adjacent feed roll 181 and driven at a peripheral speed high with respect to the feed roll whereby the barbs are stripped. A suction separator is provided adjacent the outlet from the stripper roll, the separator comprising a pair of deflectors 185, 186 which direct the shafts into a suction conduit 187 and also a suction conduit 188 opening adjacent the outlet for picking up the barbs and conveying them to any desired location.

While I have shown and described various specific methods and apparatus, I desire it to be understood the present invention is not limited thereto except as so limited by the subjoined claims.

Having now described my invention, I claim:

1. In a feather stripping machine, means to arrange feathers with their quill ends in one direction, a member mounted for rotation and provided with outwardly extending arms, a fixed member having a grooved surface in proximity to the path of said member mounted for rotation, and cooperating therewith to grip feathers arranged by said means and to convey them, quill ends first, a pair of feed rolls arranged to be driven and positioned to grip and feed feathers conveyed by said members.

2. In a feather stripping machine, means to

arrange feathers with their quill ends in one direction, a driven endless belt arranged with an end of one run thereof adjacent said means and the other end of said run spaced therefrom, suction means to draw air through said belt whereby feathers arranged by said means adhere to the belt and are conveyed thereby, and feeding means arranged to receive feathers from said belt and feed them, quill ends first.

3. A feather stripper comprising means to arrange and feed feathers, quill ends first, a roll provided with grooves of a size to receive the shafts of said feathers and having surfaces between said grooves, means to press against said surfaces comprising a belt arranged to contact the periphery of said roll throughout a substantial portion of the periphery thereof.

4. A feather stripper comprising means to arrange and feed feathers, quill ends first, a roll provided with grooves of a size to receive the shafts of said feathers and having surfaces between said grooves, an endless belt arranged to contact said roll and to move therewith throughout a substantial portion of the periphery of said roll, said roll being arranged to be driven at a higher peripheral speed than the feathers are fed by said means.

5. A feather stripping machine comprising means to arrange and feed feathers, quill ends first, a roll provided with grooves of a size to receive the shafts of feathers and having surfaces between said grooves, an endless belt arranged to contact said roll, a plurality of pinch rolls arranged to hold said belt against said roll throughout a substantial portion of the periphery thereof.

6. In a feather stripping machine, a roll provided with a plurality of grooves of a size to receive the shafts of feathers and with surfaces between said grooves, means to press against said roll and to travel therewith, a conduit to which suction is applied having an opening adjacent said roll and said means, and deflecting means to deflect shafts of feathers and thereby prevent entry thereof into said opening.

7. In a feather stripping machine, a roll provided with a plurality of grooves of a size to receive the shafts of feathers and with surfaces between said grooves, means to press against said roll and to travel therewith, a conduit to which suction is applied having an opening adjacent said roll and said means, and deflecting means to deflect shafts of feathers and thereby prevent entry thereof into said opening, a second conduit to which suction is applied, and means to direct the shafts into said second conduit.

BOHUMIL BOUDA.
